[57] CLAIM

The ornamental design for a control panel for a free-standing range, as shown and described.

DESCRIPTION

FIG. 1 is a front perspective view of a control panel for a freestanding range showing my new design;

FIG. 2 is a front elevational view thereof;

FIG. 3 is a top plan view thereof;

FIG. 4 is a rear elevational view thereof; and,

FIG. 5 is a right side elevational view thereof, the left side elevational view being a mirror image.

The environmental structure shown in broken lines in FIGS. 1-5 is for illustrative purposes only and forms no part of the claimed design.

The undisclosed bottom is plain and unornamented.

FIG. 1

FIG. 2

FIG. 3

FIG. 4

FIG. 5
